RAILWAY CAR TRUCK

George E. Dath, Mokena, Ill., assignor to W. H. Miner, Inc., Chicago, Ill., a corporation of Delaware

Application May 26, 1944, Serial No. 537,385

4 Claims. (Cl. 105—197)

1

This invention relates to improvements in railway car trucks.

One object of the invention is to provide in a railway car truck simple and efficient means for effectively snubbing the action of the usual truck springs by frictionally resisting upward and downward movement of the truck bolster.

A more specific object of the invention is to provide friction means for snubbing or dampening the action of the truck springs of a railway car comprising spring actuated rocking friction members mounted in pockets in the truck side frames at the bolster guide portion thereof and engaging opposite sides of the bolster to frictionally oppose upward and downward movement of the bolster.

Other objects of the invention will more clearly appear from the description and claims hereinafter following.

In the drawing forming a part of this specification, Figure 1 is a side elevational view of a portion of one of the side frames of a railway car truck and the associated bolster and truck springs, illustrating my improvements in connection therewith. Figure 2 is a longitudinal, horizontal sectional view, corresponding substantially to the line 2—2 of Figure 1. Figure 3 is a detail perspective view of a friction rocker employed in my improved construction.

In said drawing, 10 indicates one of the side frame members of a railway car truck. The side frame member is in the form of a casting and has a top member 11 and a bottom member 12 connected by vertical sections 13—13. As will be understood by those skilled in this art, the car truck includes two side frame members 10—10, a truck bolster 14, and truck springs 15. The opposite ends of the bolster 14 are guided between the vertical sections 13—13 and 13—13 of the truck side frames and the bolster is supported by the truck springs 15 of the two side frames, which springs rest on the bottom members 12—12 of the side frames. The truck bolster 14 supports the car body by means of the usual body bolster.

As shown in Figure 1, the sections 13—13 are inwardly offset at the upper ends thereof to provide guides 16—16 which cooperate with guide seats 17—17 at the sides of the bolster 14. The vertical sections 13—13 of each side frame casting 10 include a vertical wall 18 and inner and outer webs 19 and 20 at right angles to said wall, which webs, together with similar webs on the top and bottom members 11 and 12, form the inner and outer side walls of the casting.

My improved snubbing means comprises

5 broadly a pair of rocking friction members A—A carried by each side frame member and frictionally engaging the bolster at the opposite sides, and a pair of springs B—B associated with each rocking member for tilting the same against the bolster in frictional contact therewith.

In carrying out my invention, I provide pockets 21—21 in each side frame at each side of the bolster guide opening thereof. Each pocket 21 is formed by the inner and outer webs 19 and 20 of the section 13 of the side frame, a vertical wall 22, forming the back wall of the pocket, a horizontal bottom wall 23, and a horizontal top wall 24. As will be evident, the walls 22, 23, and 15 24 extend from one web to the other of the side frame. The pocket 21 opens toward the bolster, said opening, which is indicated by 25, being of rectangular shape.

Each friction member A is in the form of an 20 L-shaped plate comprising a vertically disposed, flat plate section 26 and a laterally extending base portion or flange 27 at the lower end of the plate section 26. The base flange 27 has a substantially flat, upper surface 28, which forms a 25 seat for the springs B—B which cooperate with the friction member A. The underneath surface of the base flange is substantially flat, as indicated at 29, and terminates at its outer end in an upwardly curved face portion 30. The plate section 26 presents a substantially flat friction surface 31, adapted to engage the corresponding vertical side face of the bolster 14. The friction members A—A are rockingly supported in the pockets 21—21 of the truck side frame, the base 30 portions or flanges 27—27 of said friction members being supported on the bottom walls 23—23 of the pockets.

The springs B—B are in the form of helical coils, two of such coils being associated with 40 each friction member A. The two springs B—B of each friction member are interposed between the base 27 thereof and the top wall 24 of the pocket. The springs B—B are under initial compression and tend to tilt the friction member A 45 against the bolster to hold the friction surface thereof in tight frictional engagement therewith. As will be evident, the friction members A—A offer frictional resistance to up and down movement of the bolster, which is substantially 50 constant at all phases of the operation thereof. The recoil action of the truck springs 15—15—15 is effectively snubbed by the resistance provided by the friction members A—A in resisting upward movement of the bolster. As will be evident, the compression of the springs

15—15—15—15 is also retarded by the friction members A inasmuch as they offer the same amount of frictional resistance to downward as to upward movement of the bolster.

I have herein shown and described what I now consider the preferred manner of carrying out my invention, but the same is merely illustrative and I contemplate all changes and modifications that come within the scope of the claims appended hereto.

I claim:

1. In a railway car truck, the combination with truck side frame members, a truck bolster, and springs supporting said bolster on the side frame members, said side frame members being provided with bolster guides; of a pocket in one of said side frame members at the bolster guides, said pocket having a bottom wall; a rockable friction member in said pocket engaging the bolster, said friction member having a laterally projecting, platelike arm at its lower end provided with a rounded bearing projection fulcrumed on the bottom wall of said pocket; and additional springs reacting between the side frame and arm of said friction member to rock the latter against the bolster.

2. In a railway car truck, the combination with a truck side frame provided with bolster guides, a truck bolster having the vertical outer sides thereof provided with friction surfaces, and springs supporting said bolster on the truck side frame between said guides; of a pocket in said side frame at each side of the bolster at said bolster guides; an L-shaped friction plate member comprising an upstanding plate section and a laterally projecting base plate element, said member being mounted in each pocket and fulcrumed on said base plate element; and additional springs means buttressed against the side

frame and pressing on said base plate elements to rock said members against the bolster friction surfaces.

3. In a railway car truck, the combination with a truck side frame having spaced vertical bolster guides, a truck bolster vertically movable between said guides, and truck springs supporting said bolster on the side frame; of a pocket in said side frame at each side of the bolster at said bolster guides, each pocket having a horizontal bottom wall; a friction plate in each pocket, said plate having a friction surface in engagement with the corresponding outer side of the bolster; a fulcrum arm on said plate at the lower end thereof pivotally supported on said bottom wall of the pocket; and a spring under compression, said spring being mounted in said pocket and buttressed at its upper end against the side frame and bearing at its lower end on the upper side of said fulcrum arm.

4. In a railway car truck, the combination with a truck side frame having spaced vertical bolster guides, a truck bolster guided for vertical movement between said guides having the vertical outer side faces at opposite sides thereof provided with friction surfaces, and truck springs supporting said bolster on the side frame; of pockets in said side frame at opposite sides of the bolster at said bolster guides, each pocket having horizontal top and bottom walls; a friction member in each pocket, each member comprising an upstanding friction plate section and a laterally projecting fulcrum arm, said plate section bearing on the corresponding friction surface of the bolster; and a spring under compression buttressed against the top wall of said pocket and bearing on the upper side of said arm to tilt said member against the bolster.

GEORGE E. DATH.
